FUNNEL FOR MOLTEN EXPLOSIVES

Thomas F. Knight, Rockaway, and Frederick E. Tregenza, Kenvil, N. J.

Application December 17, 1942, Serial No. 469,343

4 Claims. (Cl. 86—31)

(Granted under the act of March 3, 1883, as amended April 30, 1928; 370 O. G. 757)

The invention described herein may be manufactured and used by or for the Government for governmental purposes without the payment to us of any royalty thereon.

This invention relates to the loading of explosive shells, more particularly, of the type provided with a threaded mouth into which the fuse is screwed and with a cavity formed in the body of inert explosive material for receiving the booster or other detonating agent. In loading shells of the character described it has been the practice heretofore to fill the shell with molten inert material and after the same had cooled to sufficient hardness, to drill or otherwise machine the booster cavity into the body of inert material. One of the prime objects of this invention is to provide for the formation of the booster cavity simultaneously with the loading of the shell. This is achieved by a novel form of funnel. Allied with this object, a further object is to devise the novel form of funnel in a manner to protect the shell threads during the pouring operation, so as to obviate the need of subsequent remachining or cleaning.

It is necessary that the bottom of the booster cavity be faced or machined to a smooth surface. This has been done heretofore by the use of drills or other facing tools. A second prime object of this invention is to implement the novel funnel of this invention—adapted, as aforementioned, to form the booster cavity simultaneously with the loading operation—with means for facing the bottom of the cavity at, or preparatory to, the removal of the novel funnel.

For the attainment of these and such other objects of invention as may hereinafter appear or be pointed out, we have shown one embodiment of our invention in the accompanying drawing, wherein:

Fig. 1 illustrates the improved funnel;

Fig. 2 is an elevational sectional view thereof;

Fig. 3 is a sectional elevation of the improved funnel shown in position in a shell, during the loading thereof;

Fig. 4 illustrates the lower portion of the funnel with the surfacing blade and its holding ring removed; and

Fig. 5 shows the surfacing blade.

The improved funnel 10 has the usual tapered portion 11 and is provided with shoulder 12 by which the funnel rests on, and is centered in, the shell 1. The funnel has a longer-than-usual spout portion 13 extending through the threaded mouth 2 and the smooth throat 3 of the shell. Spout portion 13 of the funnel is made longer

than would be required merely for conducting the molten inert material into the shell, for the purpose of providing means for forming the booster cavity simultaneously with the loading operation. For this purpose the lower portion of the spout is extended a distance depending upon the required depth of the booster cavity. It will be noted from Fig. 3 that the outside diameter of the core portion 14 of the spout is such that this portion fits snugly in the throat 3 of the shell; the purpose of this snug fit is to prevent the molten inert material from passing between core 14 of the spout and throat 3 of the shell and from reaching and contaminating threads 2.

After placing the improved funnel in loading relation to the shell, as shown in Fig. 3, molten explosive is poured into the shell through the funnel to a height slightly below the funnel top, the object being to provide a sufficient head or riser to eliminate cavitations during solidifications. After solidification the funnel is struck a sharp blow with a mallet to break off the riser column of hardened inert material and permit removal of the funnel, the break occurring at or near the bottom of the spout, more particularly, at the bottom or mouth of the core portion 14 thereof. By reason of the aforescribed core 14, there will be provided, after solidification, a booster cavity of the required diameter and depth.

The bottom surface of the cavity, however, is in a rough condition because of the nature of the break caused, as just described, between the funnel riser and the body of solid explosive material. This surface must then be drilled or otherwise faced to a smooth condition.

As pointed out in the statement of invention, the second prime object of this invention is to implement the funnel with means for facing the bottom surface of the booster cavity. For this purpose the core portion 14 of the spout is provided with a slot 15, see Fig. 4, within which is received knife 20 (shown itself in Fig. 5, and in position in the funnel in Figs. 2 and 3). For the purpose of holding knife or cutter 20 securely in place, an annular groove 16 is provided encircling the core portion 14 of the spout near its mouth, and adapted to receive a spring snap ring 36. The cutter 20 is provided with a slotted recess 26 at each end, Fig. 5, adapted when the cutter is positioned in the funnel, to align with the annular groove 16 of the funnel and to receive snap ring 36. The lower edge of cutter 20 is beveled to form a pair of oppositely facing

cutting edges 21. Preparatory to withdrawing the funnel, but subsequently to the breaking off of the rise (as above described) the funnel is rotated one or more turns to cause the cutter 20, more accurately, its pair of cutting edges 21, to face the bottom surface of the booster cavity to a smooth finish.

We claim:

1. A device for loading explosive shells of the type provided with an internally threaded fuse mouth and for forming a booster cavity in the body of inert explosive and smoothing its bottom surface, comprising a funnel provided with a spout portion extending beyond the said shell threads, the outside diameter of the spout below the said threads being adapted to snugly fit in the throat of the shell whereby the molten explosive is prevented from reaching the said shell threads, the lower portion of the spout being adapted by diameter and length to form the booster cavity in the said molten explosive, the bottom edge of the said spout portion being provided with a pair of diametrical opposed slots, and the outer surface of the spout portion being provided near its edge with a circumferential groove, a cutter adapted to be received in the said pair of slots and provided with a pair of end slots aligned with the said spout groove, and a snap ring adapted to fit in the said spout groove and cutter slots to hold the cutter in place, the lower edge of the cutter being bevelled to form a pair of oppositely facing cutting edges.

2. A device for loading explosive shells of the type provided with an internally threaded fuse mouth and for forming a booster cavity in the body of inert explosive and smoothing its bottom surface, comprising a funnel provided with a spout portion extending beyond the said shell threads, the outside diameter of the spout below the said threads being adapted to snugly fit in the throat of the shell whereby the molten explosive is prevented from reaching the said shell threads, the lower portion of the spout being adapted by diameter and length to form the booster cavity in the said molten explosive, the bottom edge of the said spout portion being provided with a pair of diametrical opposed slots

and the outer surface of the spout portion being provided near its edge with a circumferential groove, a cutter provided with a bevelled cutting edge adapted to be received in the said pair of slots and provided with a pair of end slots aligned with the said spout groove, and a snap ring adapted to fit in the said spout groove and cutter slots to hold the cutter in place.

3. A device for loading explosive shells of the type provided with an internally threaded fuse mouth and for forming a booster cavity in the body of inert explosive and smoothing its bottom surface, comprising a funnel provided with a spout portion, the lower portion of the spout being adapted by diameter and length to form the booster cavity in the said molten explosive, the bottom edge of the said spout portion being provided with a pair of diametrical opposed slots, and the outer surface of the spout portion being provided near its edge with a circumferential groove, a cutter adapted to be received in the said pair of slots and provided with a pair of end slots aligned with the said spout groove, and a snap ring adapted to fit in the said spout groove and cutter slots to hold the cutter in place.

4. A device for loading explosive shells of the type provided with an internally threaded fuse mouth and for forming a booster cavity in the body of inert explosive and smoothing its bottom surface, comprising a funnel provided with a spout portion extending beyond the said shell threads, the outside diameter of the spout below the said threads being adapted to snugly fit in the throat of the shell, whereby the molten explosive is prevented from reaching the said shell threads, the lower portion of the spout being adapted by diameter and length to form the booster cavity in the said molten explosive, the bottom edge of the said spout portion being provided with a pair of diametrical opposed slots, a single cutter adapted to be received in the said pair of slots and means for retaining the cutter in the said slots, the lower edge of the cutter being bevelled to form a pair of oppositely facing cutting edges.
